UNITED STATES PATENT OFFICE.

ROBERT BURRIS, OF HOUSTON, TEXAS.

RAILWAY RAIL.

Application filed March 27, 1922. Serial No. 547,151.

To all whom it may concern:

Be it known that I, ROBERT BURRIS, citizen of the United States, residing at Houston, in the county of Harris and State of Texas, have invented certain new and useful Improvements in Railway Rails, of which the following is a specification.

This invention relates to new and useful improvements in a railway rail.

- 10 One object of the invention is to provide a railway rail which is formed of the original T rail, now in common use, in combination with a supplemental outside rail having an overlapping tread portion which, in 15 use, lies upon the tread of the T rail and which takes the wear and which, when worn, may be replaced, from time to time without renewing or replacing the T rail, thus lessening the cost of replacing railway tracks.
- 20 Another object of the invention is to provide a railway rail which will be strong and durable, which will not be liable to overturn or spread and which has a much wider supporting base than the ordinary rail now in 25 common use.

With the above and other objects in view the invention has particular relation to certain novel features of construction, arrangement of parts and use, an example of which 30 is given in this specification and illustrated in the accompanying drawings, wherein:—

Figure 1 is a side view of the rail, mounted upon the ties and showing the joint between abutting ends of the supplemental rail.

35 Figure 2 shows a side view of the rail, showing the joint between the abutting ends of the T rail.

Figure 3 shows an enlarged transverse sectional view of the rail.

40 Figure 4 shows a side view of the supplemental rail and,

Figure 5 shows a brace lug employed.

Referring now more particularly to the drawings, wherein like numerals of reference designate similar parts in each of the figures, the numerals 1, designate the railway ties, mounted upon which is the ordinary T rail 2, whose abutting ends are clamped together by means of the ordinary fish plates 3, 3, all spiked to the ties by means of the spikes 4 of common use.

On the outside of each rail 2, forming the track there is a supplemental rail 5. The outer edge of this rail is formed with a wide base 6 which rests upon the ties and is secured in place by means of the spikes 7.

This supplemental rail is formed with an overturned tread portion 8 which lies upon the tread of the T rail 2 and the intervening part 9 of the supplemental rail inclines toward the tread of the T rail thus forming a brace which prevents the T rail from spreading or overturning due to the pressure from passing locomotives. The abutting ends of the supplemental rail 5 are bolted to the T rail by means of the bolts 10, 10, Figure 1. These bolts pass through the fish plates 3, 3 and through the web of the T rail as well as through the supplemental rail, all of which is illustrated in Figure 3, and the supplemental rail is further secured to the T rail by means of the bolts 11, 11 located at suitable places and similar to the bolts 10.

In order to further brace and strengthen the T rail 2 I have provided suitable lugs 12, 75 wedge shaped in form. These lugs are interposed between the underside of the tread of the T rail 2 and the supplemental rail, and are bolted in place by means of the bolts 10 and 11. The bolts 10 and 11 are secured 80 in place by means of the nuts 13 which are screwed onto the threads thereof and which abut against wedge shaped washers as 14, shown in Figure 3. A very strong rail is thus provided having a very wide supporting base and braced so as to guard against the spreading of the tracks or the overturning of the rails. In replacing the tracks it is only necessary to remove and replace the supplemental rail 5 as the T rails 2 do not 90 sustain any wear and will last indefinitely.

What I claim is:—

1. A railway rail including the combination of a T rail and a supplemental rail formed with a tread which lies over the tread of the T rail, and having a supporting base alongside the base of the T-rail.

2. A railway rail including the combination with a T rail of a supplemental rail secured to the outside of the said T rail and formed with a wide base and an overlapping tread which lies upon and extends beyond the tread of the T rail.

3. A railway rail including the combination with a T rail of a supplemental rail 105 disposed along the outer side of said T rail and formed with a wide base which extends beyond the base of the T-rail and a tread which overlies the T rail tread.

4. A railway rail including the combination with a T rail of a supplemental rail disposed along the outer side of said T rail

and formed with a wide base which lies alongside the base of the T-rail and a tread which overlies the T rail tread, and bolts securing the T rail and supplemental rail 5 together.

5. A railway rail including the combination with a T rail of a supplemental rail disposed along the outer side of said T rail and formed with a wide base and a tread which 10 overlies the T rail tread, bolts which secure the T rail and supplemental rail together

and brace lugs interposed between said supplemental rail and T rail and held in place by said bolts.

In testimony whereof I have signed my 15 name to this specification in the presence of two subscribing witnesses.

ROBERT BURRIS.
